WATERCRAFT

Yves Anselme Lapointe, Quebec, Quebec, Canada,
assignor to Bombardier Limited, Valcourt, Quebec, Canada

Filed Oct. 2, 1968, Ser. No. 13,809

Term of patent 14 years

Int. Cl. D12—06

U.S. Cl. D71—1

FIGURE 1 is a view from the top of the watercraft showing my new design;

FIGURE 2 is a view from the side of the watercraft showing my new design;

FIGURE 3 is a view from the front of the watercraft showing my new design;

FIGURE 4 is a view of the watercraft showing my new design.

The dominant features of my design reside in the portions shown in full lines.

I claim:

The ornamental design for a watercraft, as shown and described.
